UNITED STATES PATENT OFFICE.

WILLIAM A. SHADD, OF NORTH BUXTON, ONTARIO, CANADA.

TRACTION-ENGINE.

SPECIFICATION forming part of Letters Patent No. 355,891, dated January 11, 1887.

Application filed June 4, 1886. Serial No. 204,134. (No model.)

To all whom it may concern:

Be it known that I, WILLIAM A. SHADD, of North Buxton, in the Province of Ontario and Dominion of Canada, have invented new and useful Improvements in Traction-Engines, of which the following is a full, clear, and exact description.

My invention relates to traction-engines adapted for plowing or thrashing or for hauling ditching-machines or other loads.

The invention relates more particularly to an apparatus for guiding the engine, the object being to provide an effective, easily-handled steering-gear, which, when adjusted by hand-levers, will be operated by the power of the engine itself, and to so construct the engine that it may be turned short around to either side, and within its own length, if necessary.

20 The invention consists in certain novel features of construction and combinations of parts of the traction-engine, all as hereinafter fully described and claimed.

Reference is to be had to the accompanying drawings, forming a part of this specification, in which similar letters of reference indicate corresponding parts in all the figures.

Figure 1 is a side elevation of a traction-engine embodying my improvements. Fig. 2 is a plan view thereof, with parts broken away and in section and with the boiler indicated in dotted lines. Fig. 3 is an enlarged vertical sectional elevation of the forward truck and steering-gear of the engine and adjacent parts of the frame, steam-cylinders, and boiler. Fig. 4 is a central vertical sectional elevation of the parts shown in Fig. 3, and taken at a right angle therewith. Fig. 5 is an inner face view, partly broken away, of one of the forward truck-wheels and applied clutch mechanism; and Fig. 6 is a view of the driving-gearing and its supporting-frame, taken on the line $x x$, Fig. 4, and as viewed in direction of the arrows.

The traction-engine is supported on forward wheels, $A A'$, and hind wheels, $B B$, placed on axles $a b$, respectively, the axle b having bearings in the engine-frame C , on which the boiler D is mounted, and the forward axle, a , having bearings at $e e$ in a heavy arched bridge-piece, E , on which rests the forward downwardly-bowed head-piece, F , which is bolted to the forward end of the frame C , on

which latter are supported the engine steam-cylinders C' , from pistons in which the rods $c c'$ connect to disk-wheels c^2 on a shaft, C^2 , journaled across the engine-frame. On the shaft C^2 are fitted the eccentrics c^3 , which connect to usual link-motions c^4 , from which the valve-stems c^5 are operated to actuate the valve for admitting the steam from the boiler D to the steam-cylinders and exhausting the steam from the cylinders through proper pipe-connections. The link-motion is controlled by the angle-lever c^6 , rod c^7 , and the lock-lever c^8 , within reach of the attendant.

On the shaft C^2 there is fixed a pinion, b' , which meshes with a gear-wheel, b^2 , and a gear-wheel, b^3 , which meshes with wheel b^2 , fast on a transverse shaft, b^4 , journaled in the frame C . The shaft b^4 carries pinions $b^5 b^6$ at opposite ends, and these pinions mesh with gear-wheels $b^6 b^6$, fixed to the opposite hind wheels, $B B$, of the engine, and whereby power is transmitted from the shaft C^2 , driven by the pistons in cylinders C' , to move the engine either forward or backward along the road.

The bridge-piece E and head-piece F , where they meet, are free to turn in a horizontal plane and make a kind of a fifth-wheel connection of the forward truck, $A A'$, of the engine with the engine-frame, and a steel wear-plate, f , is interposed between the bridge and head $E F$, said plate f being fastened preferably to the bridge E , and having a lip or flange, f' , which fits an annular recess in the head F , and prevents lateral movement of these two parts $E F$.

The inner faces of the bridge and head $E F$ are concaved vertically across their joint with each other, to receive the convexed end parts, $g h$, or tubes $G H$, respectively, which project above the head F and below the bridge E , and have fixed to them, respectively, the bevel gear-wheel I and the bevel-pinion J . The head-piece F is provided with a backwardly-extending bracket or arm, F' , in which is journaled one end of a shaft, K , which ranges longitudinally of the engine-frame, and is journaled at its other end in a yoke or saddle, L , supported from the main power-shaft C^2 of the engine, and from which power is transmitted to rotate the shaft K by means of bevel-gears $l k$ on the shafts C^2 and K , respectively. On the forward axle, a , there is fixed a bevel gear-wheel,

M, with which the aforesaid bevel pinion J engages, and on the shaft K there is fixed a bevel-pinion, N, which engages the bevel gear-wheel I, and whereby when motion is imparted to the two-part tubular shaft G H motion also will be given the axle *a* from the main power-shaft C.

The inner or meeting ends, *g h*, of the parts G H are formed with intermeshing teeth, or as 10 a clutch, and whereby they may have partial disengagement at any point around their periphery, to accommodate the positions of the forward wheels, A A', as they move over uneven ground, and also to accommodate any 15 slight rocking motion of the boiler on the wheeled trucks and frame.

With this construction it is obvious that there is nothing in the way of the free swinging movement of the forward axle and wheels 20 entirely around under the boiler, or with the axle *a* in line with the boiler, for making very short turns in guiding or steering the engine to either side by means of clutch mechanism connected to the forward wheels, A A', as next 25 described.

The clutch mechanism arranged with the wheels A A' is alike for each wheel; hence a description of the clutch arranged with wheel A will answer for either wheel, as follows: 30 To the spokes of wheel A there is bolted firmly a friction-rim, O, and outside of this rim there are placed the opposite semicircular brake-shoes or plates, P P', which are connected at opposite ends to rollers R R by 35 means of links *p p'*, the one ends of which are pivoted to the opposing ends of the brake-shoes P P', and their other ends are attached to opposite sides of the rollers R R. These rollers R R are journaled at diametrically-opposite edges of a heavy disk or plate, S, which 40 is made fast by its hub *s* to the truck-axle *a*. Bolts *p² p²*, passed through radial slots *p³* in the disk S, enter the opposite brake-shoes about at their centers, and keep the shoes in 45 proper position as they are drawn inward against the friction-rim O by devices next described.

To the hub *s* of the disk S there is fixed an arm, *t*, to which there is pivoted an angle-lever, T, which connects by rods or links *t¹ t²* with the crossed outer ends, *u u*, of levers U U, which are fixed at their other ends to squared ends of the shafts of the opposite rollers, R R. The inner forked end of the lever T is connected at *t¹ t²* with a sleeve, T', which is adapted to rotate on the round portion *e* of the bridge-piece bearing *e* as the disk S and levers U U and T are carried around by and with the axle *a*, it being understood that the engine-wheels 55 A A' are loose on the axle and revolve with the axle only when the brake-shoes P P' are clamped to their friction-bands O. In a peripheral groove of the sleeve T' there is fitted loosely a collar, T'', to which at diametrically-opposite points are pivoted the one ends of 60 links *t³ t⁴*, which are connected at their other ends to the forked end or arm *v* of an elbow-

lever, V, which is pivoted at its angle to the bridge-piece E and extends by its other arm, *v'*, beneath the driving-pinion J, and directly 70 under the center of the hollow two-part shaft G H. An elbow-lever, W, acting like the one V, is pivoted to the bridge-piece E, and connects by its forked arm *w* with links *t⁵ t⁶*, which are attached to the collar T'', next to the wheel 75 A' of the engine, and the other arm, *w'*, of lever W extends also beneath the hollow shaft G H. Suitable guides, *t*, are provided on the bearings *e* for the passage of the links *t³*.

It will be seen that as the disk S, lever T, 80 and sleeve T' are turned with the axle *a* the sleeve T' will slip around within the collar T'', and the connection between the levers U, T, and V at and with wheel A, and the connection between the levers U, T, and W at and 85 with wheel A' will be maintained, and whereby when the arms *v' w'* of levers V W, respectively, are raised, the loose collars T' next the wheels A A', respectively, will be slid from said wheels, whereby the levers U U will be 90 drawn downward at their ends *u u* and the rollers R R will be turned to apply the brake-shoes P P' to the friction rims or bands O on the wheels A A' and release the brake-shoes therefrom, for purposes presently explained. 95

To the arm *v'* of lever V is connected one end of a rod, V', which passes upward through the hollow shaft G H, and at its upper end is connected to one arm of an elbow-lever, V'', which is pivoted at its angle to a hanger or 100 bracket, F', fixed to the boiler-supporting cross-beam, and to the other arm of the lever V'' there is attached a rod, V³, which extends rearward and is attached to an arm, V⁴, fixed to a shaft, *v'*, journaled on the engine-frame, and a 105 rod, V⁵, connects a lever, V⁶, on the shaft *v'*, with a hand-lever, X, arranged alongside of a toothed plate, into which a trip on the lever may spring to lock the lever in place.

To the arm *w'* of lever W is connected one 110 end of a tube, W', through which the rod V' of lever V passes, and this tube W' is attached by its upper end to an elbow-lever, W'', which is pivoted at its angle to the bracket F', and has attached to its other arm one end of a rod, 115 W³, the other end of which is attached to an arm, W⁴, fixed to a shaft, *w'*, journaled on the engine-frame, and from a lever, W⁶, on shaft *w'* a rod, W⁵, leads to a lever, like the one, X, above described and working along a locking-plate at the opposite side of the boiler. The arm *w'* of angle-lever W is bent around the drive-wheel M on the axle *a*, and the angle-levers V² W² are bent to allow the rods V³ W³, 120 with which they connect, to pass by the driving-pinion N. (See Figs. 2 and 3.) 125

By operating the lever X, connected to the rod V⁶, the brake-shoes P P' will be applied to the rim O on wheel A, and by operating the other hand-lever connected to the rod W⁵ 130 the brake-shoes P P' will be applied to the rim O on the other wheel, A'. By reason of the passage of the rod and tube V' W' through the tubular shaft G H, at the axis of motion

of the axle and wheels a A A' , the brake-shoes of either wheel may be operated, as above described, irrespective of the position of the forward axle and wheels.

5 It is obvious that when the brake-shoes P P' are applied to the rims O of both the wheels A A' the wheels will be locked to the axle a , and the engine will travel straight ahead or straight backward. To steer the engine to the 10 right hand when it is moving forward, the brake-shoes will be unclutched or released from the wheel A , in which the axle a then will turn freely, and the unclutched or fast wheel A' will turn the axle toward the right 15 until the desired course is struck, whereupon the wheel A will again be clutched by the brake-shoes to keep a straight course.

To steer the engine to the left hand, the 20 brake-shoes will be released from the wheel A' , which then will be loose on the axle, and the fast wheel A will turn the axle to the left to take the desired course, whereupon the wheel A' will again be clutched to the shaft a , as will readily be understood. By thus utilizing 25 the power of the engine for steering it a heavy engine of large power may be very easily handled, and by the described arrangement of mechanism to impart the engine's own power to turn the forward axle and wheels 30 very short turns may be made, which makes the engine very serviceable in plowing the soil.

Having thus fully described my invention, what I claim as new, and desire to secure by Letters Patent, is—

35 1. In a traction-engine, the combination, with the forward axle adapted to swing in horizontal plane, and wheels loose on the axle, of friction-bands fixed on the wheels, brake-shoes adapted to clutch said bands, and mechanism for imparting the power of the engine to the applied brake-shoes of either wheel, or both wheels simultaneously, substantially as described, for the purpose set forth.

2. In a traction-engine, the combination, 45 with the forward axle adapted to swing in horizontal plane, and wheels loose on said axle, of friction-bands on the wheels, brake-shoes adapted to clutch said bands, mechanism for imparting the power of the engine to the applied 50 brake-shoes of either wheel, or both wheels simultaneously, and connections from the brake-shoes to hand-levers for applying the shoes to the friction-bands, which connections include rods passed through the axis of horizontal rotation of the axle and wheels, substantially as described, for the purposes set forth.

3. In a traction-engine, the combination, 55 with a steering-wheel, as at A , loose on the engine-axle, and a disk, S , fixed to the axle, of a friction-band, O , fixed to the wheel, brake-shoes P P' , loosely encircling the band, rollers R R and links p p' , connecting the opposite 60 brake-shoes, P P' , and levers U U , rigidly connected to rollers R R , and adapted to turn said rollers to press the shoes to the band O , substantially as shown and described.

4. In a traction-engine, the combination, 70 with a steering-wheel, as at A , loose on the engine-axle, and a disk, S , fixed to the axle, of a friction-band, O , secured to the wheels, brake-shoes P P' , loosely encircling the band, rollers R R and links p p' , connecting the opposite brake-shoes, levers U U , rigidly connected to rollers R R , links t t' , connected to the levers U U , 75 crossed ends u u of levers U U , and an elbow-lever, T , connected to links t t' and to a sliding sleeve, T' , placed on the axle-bearing, substantially as shown and described, whereby as the sleeve is shifted lengthwise of the axle 80 the brake-shoes will be applied to the friction-band on the wheel, as herein set forth.

5. In a traction-engine, the combination, 85 with a steering-wheel, as at A , loose on the engine-axle, a disk, S , fixed to the axle, a friction-band, O , fixed to the wheel, brake-shoes P P' , loosely encircling the band, rollers R R and links p p' , connecting the opposite brake-shoes, levers U U , rigidly connected to rollers R R , links t t' , connected to the levers U U , 90 an elbow-lever, T , connected to links t t' , a sliding sleeve, T' , placed on the axle-bearing, a collar, T' , loose on sleeve T' , an elbow-lever, as at V , pivoted to the engine-frame, links v , connecting lever V with the sliding sleeve T' , 95 a rod, as at V' , connected to lever V and passed up through the axis of horizontal rotation of the wheel-support, and connections from the lever V to a hand-lever, by operating which the brake-shoes may be applied to and 100 released from the band O on the wheel A , substantially as described, for the purposes set forth.

6. In a traction-engine, the combination, 105 with the forward axle, a , and wheels A A' , mounted loosely thereon, of disks S S , fixed to the axle, friction-bands O O , fixed to wheels A A' , brake-shoes P P' , encircling the bands O O of each wheel, rollers R R and links p p' , connecting the opposite pairs of brake-shoes 110 on each wheel with the rollers, levers U U , rigidly connected to said rollers R R , links t t' , connected to the levers U U , an elbow-lever, T , connected to links t t' , a sliding sleeve, T' , placed on the axle-bearing next each wheel, 115 elbow-levers V W , pivoted to the engine-frame and connected to links v , leading to the sliding sleeves, a rod, V' , and tube W' , connected to the levers V W , respectively, and passed up through the axis of horizontal rotation of 120 the axle and wheels, and connections from the parts V' W' to independent hand-levers, by operating which the brake-shoes may be applied to and released from the friction-bands O O of either or both wheels A A' , substantially 125 as described, for the purposes set forth.

7. A traction-engine comprising the following elements: a frame, C , carrying the boiler and steam cylinders, a main driving-shaft, C' , on said frame and rotated by connections from 130 the steam-cylinders, rear driving-wheels, B B , driven from the shaft C' , forward wheels, A A' , mounted on a shaft, a , journaled in a bridge-piece, E , a head-piece, F , fixed to the frame

C, a hollow two-part shaft, G H, journaled in the parts E F, and having concaved end parts, g h, formed as a clutch, gears I J on the shaft G H, a gear-wheel, M, on axle a, a shaft, K, 5 journaled in head-piece F and in the engine-frame, a pinion, N, on shaft K, meshing with wheel I, and pinions l k on the shafts C² K, respectively, substantially as described, for the purposes set forth.

10 8. A traction-engine comprising the following elements: a frame, C, carrying the boiler and steam-cylinders, a main driving-shaft, C², on said frame and rotated by connections from the steam-cylinder, rear driving-wheels, B B, 15 driven from shaft C², forward wheels, A A', mounted on a shaft, a, journaled in a bridge-piece, E, a head-piece, F, fixed to frame C, a hollow shaft journaled vertically in the parts E F, gears I J on said shaft, a gear, M, on 20 axle a, a shaft, K, journaled in head-piece F

and in the engine-frame, a pinion, N, on shaft K, meshing with gear-wheel I, driving-pinions l k on shafts C² K, friction-bands O O, fixed to the wheels A A', disks S S, fixed to the axle next said wheels, brake-shoes P P', encircling 25 the bands, rollers R R and links p p', connecting the brake-shoes of each wheel, levers U U, rigidly connected to rollers R R, and adapted to turn said rollers to press the brake-shoes to the bands O, and connections from the levers 30 U U at each wheel A A' to hand-levers for applying the brake-shoes to the friction-bands, said connections including rods, as at V' W', passing through the tubular shaft connecting the parts E F, substantially as described, for 35 the purposes set forth.
